UNITED STATES PATENT OFFICE.

ALVIN V. ROWE, OF GALESBURG, ILLINOIS.

GATE.

1,232,609.

Specification of Letters Patent. Patented July 10, 1917.

Application filed June 19, 1915. Serial No. 34,975.

To all whom it may concern:

Be it known that I, ALVIN V. ROWE, a citizen of the United States, a resident of Galesburg, in the county of Knox and State 5 of Illinois, have invented new and useful Improvements in Gates, of which the following is a specification.

My invention relates to improvements in gates, the principal object being the provision of a gate which is simple and strong 10 in construction and may be readily and quickly assembled.

A further object is the provision of a gate, including longitudinal boards or members and transverse or cross members, the latter being of channel iron, faced inwardly and having slots therethrough located between the longitudinal boards or members so that the securing means does not pass 20 through the longitudinal boards or members.

A further object is the provision in such a structure of diagonally extending bracing means in the form of wire, extending from one set of the transverse or cross channel 25 iron members to another set.

A further object includes the improvement in the details of the hinge construction.

To the accomplishment of the foregoing and such other objects as may hereinafter 30 appear, my invention consists in the combination, construction and arrangement of parts hereinafter described, and then sought to be defined in the appended claims, reference being had to the accompanying drawings forming a part hereof, and which shows merely for the purpose of illustrative disclosure, a preferred embodiment of my invention, it being understood that various changes may be made in practice within the 35 scope of the claims without digressing from my inventive idea.

In the drawings:

Figure 1 is an elevation of a gate constructed according to my invention, mounted 45 in position for use;

Fig. 2 is an enlarged elevation of the upper hinge portion of the gate;

Fig. 3 is a bottom plan view of Fig. 2.

Referring now to the drawings the numeral 1 designates the longitudinal members of the gate which are usually wooden 50 boards or planks and the numeral 2 designates the transverse or cross pieces or members which are arranged in pairs, as shown, 55 and extend vertically. These cross pieces

are formed of channel iron faced inwardly so that the edges of the flanges bear on the longitudinal boards or members, thereby permitting ventilation and reducing the bearing surface between the cross pieces or 60 members and the longitudinal boards or members to a minimum. These cross pieces or members are secured to the longitudinal boards or members by means of bolts 3 passing through apertures in the upper and 65 lower ends of the same. It is to be noted particularly, that this securing means is used only in connection with the upper and lower longitudinal boards or members. These cross pieces or members 2 are also 70 provided with a plurality of slots 4 arranged so as to be positioned between the longitudinal boards or members 1. Bolts 5 pass through said slots 4 so as to clamp the channel iron cross pieces together adjacent 75 the intermediate longitudinal boards or members 1, the slots being provided for any necessary adjustment, due to variation in size of the longitudinal boards or members.

In connection with this gate, I also provide 80 a novel form of bracing means which includes the hook 6 adjustable as at 7 on one of the bolts 5. To this hook is connected a wire 8, which extends diagonally to one of the lowermost bolts 5 extending through 85 one of the other pairs of transverse pieces or members 2, as shown. The adjustment is provided for taking up any slack in the wire 8. It is to be noted that at the rear or hinge end of the gate the hook 6 is connected to the hinge 9, the details of which 90 will subsequently be described.

I show two forms of this bracing structure, one wherein the wire extends from the upper portion of one pair of cross pieces or 95 members 2 to the lower portion of the next adjacent pair and another form where the wire extends from the upper portion of the rear pair of cross pieces or members 2 to the lower portion of the front pair of cross pieces or members 2. It is to be understood 100 that this arrangement may be varied as desired, and also that the bracing wires may be used in pairs on opposite sides of the gate instead of merely on one side, this 105 being an obvious adaptation of the idea.

The advantages derived from the structure described, reside in the elimination of the points of contact between the metal parts of the gate and the wooden parts of the 110

gate, thereby reducing the possibility of rusting and also reducing the places where moisture can accumulate and cause rotting of the wood, with the resultant deterioration in life and efficiency of the gate.

5 This structure also permits of ready assembling of the gate and also of various necessary adjustments, due to variation in the size of the material used. There are no 10 holes through the intermediate longitudinal boards or members 1, and the number of holes through the top and bottom longitudinal boards or members 1 are reduced to a minimum.

15 It is also to be noted that these holes may be all bored in one and the same operation as the holes in the top and bottom boards or members correspond. The use of the channel iron prevents unnecessary rusting 20 and rotting, due to moisture on account of the access of air within the channel iron cross pieces or members.

25 The particular hinge construction utilized in this gate includes the strap bars or members 10 and the hinge block 11, the latter preferably being in the form of a casting of peculiar shape having the pintle receiving opening 12. This hinge block or member 11 is provided with a reduced portion 13 having the upper and lower flange 14 between which are positioned the strap members 10, these latter being inset as indicated at 15 so that the end channel iron cross pieces or members 2 will engage the strap members as 30 shown, particularly in Fig. 3. This inner portion of the hinge block or member is formed at a slight angle so as to receive the strap members 10 which extend at an angle from the upper and lower longitudinal 35 boards or members of the gate. These strap iron members are secured to the hinge block by means of bolt 16 and to the boards by means of bolt 17, an additional bolt 18 being provided to receive the hook 19, previously referred to, and to which the bracing wire is secured.

40 This particular form of hinge is very simple, composed of few parts and strong in construction. It is only necessary to bore one hole in the hinge block and three holes 45 in each of the strap members 10. The parts are readily reversible so that the same castings may be used for both the upper and lower hinges.

55 The particular form of adjustable hook used in this disclosure, is shown the best, in Fig. 2 and includes the hook or eye member 19 having the screw threaded portion 20, on which is slidably mounted the L-shaped member 21, the nut 22 being provided for adjustment. The lower portion of this L-shaped member 21, is provided with a grooved lug or extension 23 about which the wire is adapted to be looped, as shown. This 60 is merely one form of a device which is used

to provide the necessary adjustable connection.

What I claim is:—

1. A gate including in combination, a plurality of longitudinal members and a plurality of transverse members arranged in pairs on opposite sides of said longitudinal members, said transverse members being secured to the upper and lower longitudinal members and having longitudinally extending adjusting slots located between the intermediate longitudinal members and bolts passing through said adjusting slots to clamp the transverse members to the longitudinal members. 70

2. A gate, including in combination, a plurality of longitudinal members, a plurality of transverse members arranged in pairs on opposite sides of said longitudinal members, said transverse members being formed of channel iron facing inwardly, bolts for securing said transverse members to the top and bottom longitudinal members, said transverse members also having a plurality of longitudinally extending adjusting slots located between said longitudinal members and bolts passing through the aligned adjusting slots in the pairs of said transverse members to clamp the transverse members to the longitudinal members. 80

3. A gate, including in combination, a plurality of longitudinal members, a plurality of transverse members arranged in pairs on opposite sides of said longitudinal members, said transverse members having a plurality of slots provided therein and arranged between said longitudinal members, and bolts passing through the aligned slots in each pair of said transverse members to clamp the transverse members to the longitudinal members, and bracing means in the form of a wire connected to one of said bolts of one of said pairs of transverse members and extending diagonally to one of said bolts of another pair of said transverse members. 100

4. A gate, including in combination, a plurality of longitudinal members, a plurality of transverse members arranged in pairs on opposite sides of said longitudinal members, said transverse members having a plurality of slots provided therein and arranged between said longitudinal members, and bolts passing through the aligned slots in each pair of said transverse members to clamp the transverse members to the longitudinal members, and bracing means in the form of a wire connected to one of said bolts of one of said pairs of transverse members and extending diagonally to one of said bolts of another pair of said transverse members, and means for adjusting the tension of said wire. 115

5. A gate including in combination, a plurality of longitudinal members, a plurality of 120

transverse members arranged in spaced relation and connected to said longitudinal member and diagonally extending bracing means secured to the upper portion of each 5 transverse member and extending to the lower portion of the adjacent transverse members, the diagonally extending bracing members being arranged alternately on opposite sides of said longitudinal members 10 and including means for adjusting the tension of said diagonally extending bracing members.

6. In a gate having a plurality of longitudinal members and a plurality of transverse members secured together, diagonally 15 extending bracing means connecting one of said transverse brace members with another, said bracing means including a connecting means having an eye provided with a threaded portion, an L-shaped member having a 20 sleeve slideable on said eye member, a nut on the screw threaded portion thereof, to limit the movement of said sleeve, said diagonal bracing means being connected to the other 25 end of said L-shaped member.

7. A gate including in combination, lon-

gitudinal members and transverse members arranged in pairs on opposite sides of said longitudinal members and secured thereto, 30 bracing means in the form of a wire secured to one of said pairs of transverse members and extending diagonally to another pair of transverse members, and means for connecting said bracing means to said transverse members including an eye having a threaded portion, and L-shaped member having a sleeve slideable on said eye member, a nut on the screw threaded portion thereof to limit the movement of said sleeve, said wire being connected to the other end of said L-shaped 35 member.

8. A gate including in combination, a plurality of longitudinal members and a plurality of pairs of transverse members arranged on opposite sides of the longitudinal 40 members and secured thereto, a plurality of bracing means in the form of wires, secured to the upper portions of said pairs of said transverse members and extending to the lower portions of the adjacent pairs of 45 transverse members.

ALVIN V. ROWE.
